OIL BURNER

Rex E. Moule, Detroit, Mich.

Application October 29, 1935, Serial No. 47,304

3 Claims. (Cl. 158—4)

This invention relates to oil burners, and particularly to the type of domestic burner especially designed to be located in the ordinary hearth area of a furnace.

5 An object of my invention is to provide an oil burner wherein the fuel oil distributing cup is positioned below the hearth line, thereby eliminating the tendency of the fuel oil to carbonize or " coke" in the cup because of excessive heat. 10 Another object of the invention is to provide an oil burner having an air supply means of such construction and so arranged that it will deliver at a low velocity the necessary amount of air for efficient combustion.

15 Another object of the invention is to provide a burner of such construction and arrangement of parts as to create effective and concentrated air turbulence immediately above the air inlet, thereby producing a "lazy" flame without the 20 danger of having the flame snuffed out or extinguished while in use.

Another object of the invention is to provide an oil burner in which the combustion is graduated so that detonation noises are reduced to a 25 minimum.

Another object of the invention is to create a new type of flame partially formed by the projection of liquid fuel to a flame propagating zone, and then completed to a dome shape by gasification of the projected liquid fuel and the supply of combustion supporting oxygen in a central turbulent swirl.

With the foregoing and other objects in view it will be seen that my invention consists of various novel features of construction, as well as the novel combination and arrangement of parts which are more fully hereinafter described and claimed.

In the accompanying drawing forming a part 40 of this application:

Figure 1 is a vertical sectional view of my invention set in a furnace hearth, partly broken away.

Figure 2 is a top plan view of the oil burner embodying my invention, on the line 2—2 of Figure 1.

Figure 3 is a top plan view of the oil burner embodying my invention, on the line 3—3 of Figure 1.

50 It must be explained that the mechanical parts of the invention as hereinafter described will all be quite simple in construction, and even the general arrangement may appear quite ordinary; and for this reason I want to emphasize the essential and important features of novelty.

I think it is generally recognized that oil burners of the domestic type are of four classes. First, the "gun" type which simply projects a mixture of oil and air from a nozzle into a combustion chamber, (generally pot-like and of refractory material) wherein the mixture of oil and air is broken up by impingement to a degree that will support combustion but quite susceptible to carbonization or smoke due to partially burned oil globules. Second, the "ring" type wherein the oil is whirled around at high speed with air at high velocity in an attempt more completely to distribute the combustible particles over a large ring-shaped area but still with a forced impingement and burning causing sporadic combustion with resultant carbonization and smoke due to incomplete gasification of the oil. Third, the "disc" type of burner, in which the fuel oil is fed to a rotating disc or spread over an area to minutely atomize the oil and again mechanically mix the same with the air for supporting combustion; but this type is also susceptible to reactive flame propagation causing explosive burning of the fuel oil and resultant noise, and carbonization and overheating of the distributing disc.

25 The fourth type of burner is the "generative" type wherein the oil is fed through filtering material such as an asbestos wick used in some kerosene stoves. This type, however, has the disadvantage that it requires a considerable time to 30 change from a "low" to a "high" fire or flame, and the air during such change is quite out of proportion and excessive. This type is silent as the air cannot be forced to co-mingle with fuel faster than the fuel gasifies.

35 In the present invention I want to point out particularly that the fuel oil is delivered to an outer zone and ignited electrically or by a pilot light, with a minimum quantity of air to support combustion and used to gasify the fuel oil quickly; 40 then the flame is supported by a central core or heart of turbulent air to complete a perfect dome of "Bunsen" type lazy blue flame without smoke due to unburned particles of fuel and without noise. In other words, the flame is truly the 45 "Bunsen" type flame.

I believe I am the first to produce a "Bunsen" type flame over a comparatively large area such as required in a domestic oil burner, and with a circle or corona of generating flame to enclose a 50 dome-shaped, blue-white "Bunsen" type flame without noise or soot, with a wide range of adjustment and with a maximum of efficiency as determined by stack gas analysis.

55 Referring now more specifically to the drawing,

the numeral 10 indicates a cast-metal annular supporting ring preferably formed with an outer flange 11 and an inner flange 12, and having three orifices into which are set three supporting posts 14 made adjustable as by the threaded feet 15 to support and level the ring 10 in the center of the combustion chamber hearth which is built in the approximate area usually occupied by the fire-grates by resting a sheet-metal plate 16 on the outer ledge 11, said plate extending laterally to the fire-box wall 13 of the furnace and being covered on top by a facing of refractory material forming a hearth 17.

It must be understood that the hearth may be of any shape and approximate dimensions, just so it covers the space between the supporting ring 10 and the furnace side walls, and separates the customary ash-pit from the fire-box or chamber, and the ash-pit opening (not shown) allows free entrance of air to the space underneath the hearth.

The ring 10 and hearth 17 are finished on top by a burner plate 18, which may be built in of sectional tile or made of cast-iron sections, just so it is formed circular and rests on the supporting hearth 17 and the supporting ring 10.

In the drawing this plate is shown cast in suitable sections with the central opening 19 around a depending flange 20 resting on the ledge 12 of the supporting ring and extending flat and laterally to the circular outer upstanding border flange 21, defining the diameter of the flame and forming what may aptly be termed a corral for the liquid fuel and resultant gas generation and flame.

Immediately inside the border flange 21 the flame plate is formed with a trough 22 and fingers 23 projecting upwardly from the bed of the trough to assist in gasifying the fuel oil fed to the trough as hereinafter described. The central opening through the supporting ring 10 and the burner plate 18 is provided with a pair of damper plates 24, each having a central opening 25 and "hit and miss" openings 26 whereby they may be rotated one in relation to the other to throttle or control the amount of air passing therethrough. The damper plates 24 are shown in the drawing supported on the ledge 12, but it will be understood that they may be supported elsewhere in the central opening.

So far I have described the stationary parts proper which really form the hearth of the furnace and from which are floated the rotating parts including, as hereinafter described, an electric motor that might develop any mechanical vibration to resound or be transmitted through the stationary parts having direct connection with the furnace.

The rotating parts of my invention are fully floated and resiliently supported on a sheet-metal plate 27 fastened by adjustable screws 28 to the hearth ring 10. The plate 27 has the central opening 28 around which a rubber ring 29 is fastened as by screws 30, and this rubber ring in turn is secured to a motor 31 around the bearing at one end as by screws 30, whereby the motor is suspended vertically and in the center of the entire assembly, with the shaft 32 extending upwardly through the central opening 28 in the supporting ring 10. Electric wires, as indicated at 33, are of course provided and connected to suitable central switches for stopping and starting the motor, fuel oil and pilot light, as required.

75 The motor shaft 32 carries at its upper end

the air and fuel oil distributing means, which constitute some of the salient features of my invention. That is, they are especially constructed to produce a novel form of oil and air distribution and the resultant dome-shaped "Bunsen" type flame.

The fuel supplying device 37 consists of an inverted fuel cup, frusto-conical in shape, the side of the cup extending downward to the smaller end of the cone. At the lower edge of the cone the cup is turned inward and upward to form a trough 38. The closed end wall or bottom 35, of the cup has centrally secured thereto a nut 36, by means of which the fuel supplying device may be screwed upon the shaft 32.

The fuel oil cup 37 has at its divergent upper end two distributing tubes 39 extending from the disc 35 to the outer edge of the plate 33 where said plate is turned down at 40.

20 The oil cup 37 is supplied with fuel oil by a goose-neck tube 41 supported by and extending upwardly from the motor casing, and connected to a fuel oil supply and a control valve (not shown), whereby oil is fed into the trough 38 25 of the fuel oil cup each period the motor is running; and from the trough 38 the fuel oil will be carried by centrifugal force up the side wall of the fuel oil cup to the tubes 39, and be discharged from the outer ends thereof and sprayed 30 into the trough 22 of the flame bed plate 18.

The air distributor is rigidly fixed on the end wall or bottom 35 of the fuel cup. It consists of a rotary fan having a small number of blades 34 riveted or otherwise radially secured on the 35 wall 35 of the fuel cup, and carrying at their upper edges a sheet metal cowling plate or disc 33, to which also the fan blades are radially secured by riveting or otherwise. The blades are open and unconnected except by the cowling 40 plate 33. Plate 33 has a central opening 303, which permits air to pass directly to its upper face, and thereby avoid undue fall of pressure in that region.

45 The plate 33 is rather widely spaced above the hearth 17, so that the flow of air between the said plate and the hearth is practically unobstructed, there being no barrier other than a narrow flange or bead around the edge of plate 33 which serves to stiffen the same and afford 50 means for securing in place the ends of fuel pipes 39.

The damper plates 24 heretofore mentioned, serve to control the flow of air into the furnace in such manner as to avoid building up undue pressure and velocity of air in the combustion chamber.

From the construction shown it is possible to rotate the distributor with sufficient velocity to project the oil to the peripheral ring without 60 atomization of the oil and yet to impart to the air only a low velocity, whereby a gentle turbulence is produced in the air.

As the burner is a "Bunsen" type, it is preferably used with an "on and off" control, as a ring 65 of flame around the trough 22 is too extensive a circle to maintain a "low" burning flame. It is therefore desirable to use a pilot flame or other igniting device, such as that shown at 41, where a gas pilot is arranged to direct a pilot 70 flame across a portion of the flame bed trough to ignite the fuel oil when first thrown thereon immediately after the motor 31 is operated to supply fuel oil and air, and of course in normal operation the fuel oil is readily gasified as the 75

flame bed plate and trough are naturally quite hot from the previous fire and the heat stored about the entire furnace structure.

It must be emphasized that the flame resulting from the apparatus just described is exceptional in character insofar as its efficiency and the effect upon the operating parts are concerned; and just as the thin sheet-metal parts of a Bunsen burner do not melt down as compared with the 5 heavy cast-iron grate bars of a coal-fired furnace, just so the flow of air past the rotating parts of the burner as above described continuously cool the same. In fact, the incoming air forms an effective insulating barrier between the 10 dome-shaped flame of high heat intensity and the burner, and in this connection it must further be explained that, should the central rotor or air distributing plate be formed with a regulation type of fan or impeller blades (such as 15 the well known type of Sirocco fan) the operation of the burner would be defeated, as too severe combustion would be supported about the ring of the flame bed plate, and the radiant heat would excessively heat the rotor; whereas the 20 air merely flooding therefrom, with little or no pressure, protects the air distributor or turbulator on all sides, just as the openings of a gas burner are protected, and the "hot zone" does not occur until the air and gasified fuel oil 25 combine in combustion in the dome-shaped surrounding area.

The burner as described is one that will give a quiet, blue, hovering or lazy flame of maximum intensity with a minimum amount of air; and the 30 motor is not required to run at a high speed, just so it is sufficient to distribute the fuel oil and "turbulate" the air around the flame plate to feed the amount of oxygen to support efficient combustion.

40 The character of flame is quite different from a forced flame and resembles closely the flame emanating from a fire of glowing coal without forced draft, and the admission of too much air will disperse the cupola of flame and create a 45 noise. If an automatic stack damper is used with the burner, i. e., one that is weighted to lift automatically with an increased draft proportioned to increase combustion and resultant heat, then the flow of air is practically stopped 50 until the motor starts and supplies the fuel and a comparatively small amount of air to start a full fire, which in turn automatically creates a draft to augment the supply of air.

55 My invention is chiefly directed to a controlled and definite flame generating circle, wherein a fuel oil is supplied about a ring and initially ignited with sufficient air to start combustion to supply heat for gasifying the oil about the circle, and then continuing a supply of air at low 60 velocity and in a uniformly turbulent state to co-mingle with the combustible gas emanating from the gasifying fuel oil.

In actual practice the comparatively light-weight sheet-metal air distributor or (as I prefer 65 to call it) "turbulator" will not be overheated, and the under-hung motor with its rubber mounting will be immune to the intense heat of the dome-shaped heat area of combustion that is formed over the burner plate and circumscribed 70 by the bordering fuel-catching trough.

In a furnace where the fire-box is quite large it may be desirable to spread the combustion area, and this may be accomplished by supplying more fuel oil and also more air as by auxiliary air ducts 260 spaced as desired around the flame plate and controlled by shut-off dampers 261, and the admission of air at these points will cause a spreading of the flame.

A flame may give a highly intensive heat at its impinging point, such as a blow-torch or an 10 oxygen acetylene flame when burning in the open atmosphere, but it is noisy and admittedly inefficient and impracticable for general heating purposes; such forced explosive combustion creates noise and denotes the accompanying inefficient combustion in proportion to the gases burned.

15 It will therefore be understood that the present invention is novel and useful in that it provides a means for quickly and efficiently projecting the vaporizable fuel oil over a flame propagation area, and with the same means it provides the necessary oxygen supplying air in a diffusing manner and in a controlled and metered quantity to support combustion in a natural, gradual manner, resulting in a highly efficient flame without excess air.

20 It is expected that minor modifications may be made in the particular arrangement of oil and air supply means, though the oil supply means 25 as shown absolutely prevents any coking or carbonizing of the oil, and likewise obviates any clogging of oil pipes. In like manner other details may obviously be changed without departing from the spirit and scope of my invention.

35 I claim:

1. In a furnace, a substantially horizontal hearth bounded by a circular upstanding border flange and provided with an air inlet opening arranged centrally thereof, a rotary member 40 mounted for rotation in said opening about a vertical axis comprising a centrifugal device discharging liquid fuel against said flange, means for creating a turbulence of the inflowing air above and around the center of the hearth comprising a fan having a small number of blades secured to said rotary member above the air inlet opening and a cowling plate supported thereon, and a throttling damper below said blades, whereby gentle turbulence and low velocity 45 may be imparted to the inflowing air.

2. The combination according to claim 1, in which the rotary member is mounted on the shaft of an electric motor which is secured to a rubber ring suitably supported below the hearth, 55 whereby the motor and its associated moving parts are resiliently suspended below the heat zone of the furnace.

3. In an oil burner, a combustion chamber having an air inlet in the bottom thereof, a motor mounting comprising a flexible heat insulating member spaced below said air inlet, and a motor driven fuel and air delivering unit suspended by said insulating member and having the motor below said member and shielded from 60 radiant heat from said combustion chamber, whereby said motor is protected from both radiant and conducted heat from the combustion chamber and cooled by inflowing air.

REX E. MOULE. 70
